BUTTON

Harry Chalfin, New York, N. Y.

Application July 13, 1938, Serial No. 218,914

4 Claims. (Cl. 24—113)

This invention relates to buttons made of metal, metal and fabric or similar material.

Broadly, it is an object of this invention to produce a metal button which may be covered or remain uncovered and that may be easily attached to material in a manner so as to firmly prevent such button from shifting its position and become detached from the material to which it is applied.

10 Metal buttons have been made with prongs that are bent inwardly from a flange toward the center of the button after the prongs have been inserted through the material. It is a known fact that almost all material has a certain amount of elasticity. In the wearing of a garment with such prong metal buttons attached, the material of the garment stretches in various directions so that the prongs of the button become loosened from the material and fall off. In washing or dry 20 cleaning the garment, the movement of the material causes stretching and shifting in various directions so that the metal prongs of the buttons become loose and are lost. Such constant movement of the material of the garment against the thin edges of the prongs eventually cuts the finer 25 strands of yarn producing holes of increasing size as the button gains greater freedom of movement.

It is, therefore, an object of this invention to 30 provide a metal prong button that can be readily applied to material with prongs that can be bent inwardly so as to lock the fabric to which it is applied within recesses to prevent shifting of the material.

35 Another object of this invention is to provide a type of recess at the base of the button so that the prongs when bent inwardly will readily slide into such recesses although such prongs are not bent at a perfect angle.

40 Another object of this invention is to provide a metal button having prongs and co-acting recesses for ready application and economic production and application.

45 For a fuller understanding of the nature and objects of this invention, reference is had to the following detailed description in connection with the accompanying drawing, in which:

Fig. 1 is a plan view of the inner flange member of the button.

50 Fig. 2 is a vertical section taken through line 2—2 of Fig. 1.

Fig. 3 is a plan view of the body or cover mem-

Fig. 4 is a side elevation of the cover member shown in Fig. 3.

55 Fig. 5 is a side elevation of a covered button

partly broken away to illustrate the body member locking the covering material against the flange of the inner member.

Fig. 6 is a bottom plan view of the button partly broken away, with the prongs through the material and bent to lock the material within the recesses of the inner member; and

Fig. 7 shows part of the inner body member showing a prong bent to grip the fabric within a recess.

Referring to the drawing, numeral 10 represents an inner body member, the top surface 11 of which is concave. The concave surface 11 has formed therein a series of ridges 12 and depressions or recesses 13. The side of the body 15 member 10 has a depending flange 14 from which a number of prongs 15 extend as shown in Figs. 2 and 5. The prongs 15 protrude beyond the base 16 of the flange 14 far enough so that when the prongs 15 are bent inwardly at line 16, the ends 20 17 will fit into the recesses 12.

A cover member 18 having a depending flange 19 is made slightly larger than the inner body member 10 so that a cover material 20 may be wedged between depending flange 14 of the inner 25 body member 10 and depending flange 19 of the cover member 18.

The cover material 20 may be of fabric, leather, rubber or other similar materials. The space between the two flanges 14 and 19 depends upon 30 the thickness of the material used to cover the cover member 18.

In applying the covered button, the prongs 15 of the button are passed through the fabric 21 of a garment or other article. The prongs 15 are 35 then bent at line 16, the base of the flange 14, until the prong locks the fabric 21 within the recess 12, as shown in Fig. 7.

The sides of the recesses 12 have a gradual slope so that the edges 22 of the prongs will ease 40 into place within the recesses 12. The concave surface 11 of the inner body member may be made shallow, as shown in Figs. 2, 5 and 7, so that the bottom 23 of the concave surface will not be below the base of the depending flange 45 14. In such a case, the prongs 15 will be bent to a lesser degree than 90 degrees in order to lock the fabric 21 firmly within the recesses 12, thus bringing the fabric 21 out of its normal level plane.

The concave surface 11 may also be made deeper than the base 16 of the flange 14 so that the prongs 15 will be bent inwardly to ninety degrees or greater than ninety degrees to lock the fabric 21 firmly within the recesses 12. In such 55

a case, the fabric 21 will be brought out of its normal plane bringing the fabric 21 in the center of the button below the base 16 of the flange 14.

5 The locking of the fabric 21 within the recesses 12 by the prongs 15 will firmly lock the button into position and prevent it from shifting as the fabric moves and stretches.

10 It can be readily seen that buttons as herein described may be made with a great variety of shapes and designs, such as square, triangular, diamond, hexagonal, octagonal and many other artistic and decorative shapes. Such buttons may also have higher and lower surfaces or hollow centers to vary the design, all containing the locking arrangement to prevent the movement of the button.

15 I, therefore, do not desire to limit myself to the shape and design shown in the drawing.

20 It is obvious that various other changes and modifications may be made in the details of construction without departing from the general spirit of the invention, as set forth in the appended claims.

25 I claim:

1. As a new article of manufacture, a button comprising an inner body member and a cover member for said body member, said inner body member having a concave surface portion, said concave surface portion having ridges and recesses, a flange depending from said concave surface portion, bendable prongs depending from said depending flange for piercing a material, said prongs falling within said recesses of said concave surface portion to firmly lock said button to said material.

30 2. As a new article of manufacture, a button

comprising a cover member having a depending flange, an inner body member having a depending flange and fitted within the flange of said cover member, a material covering said cover member with its edges locked between the depending flanges of said cover and said inner body members, bendable prongs depending from said depending flange of said inner body member for piercing a material, recesses within the top of said inner body member to receive the ends of said prongs for locking said button firmly to the pierced material.

3. As a new article of manufacture, a button comprising an inner body member having a depending flange, a concave surface portion having recesses between said depending flange and prongs depending from the base of said depending flange, a cover member with a depending flange for the top of said inner body member for locking a material between the flanges of said inner body member and said cover member, the recesses of said concave surface receiving said prongs to firmly lock said button against the material to which it is affixed.

4. As a new article of manufacture, a button comprising a cover member having a depending flange, an inner body member within said cover member having a concave top with recesses therein and a depending flange, a cover material over said cover member, the ends of which are firmly locked between the flanges of the cover and inner body member, depending prongs from the flange of said inner body member for piercing a material and locking said material within the recesses of said concave top of said inner body member.

HARRY CHALFIN.
